TOY FROG

Charles K. Grieder, 700 S. Lyon,
Santa Ana, Calif. 92701

Filed Sept. 25, 1972, Ser. No. 291,866

Term of patent 14 years

Int. Cl. D21—01

U.S. Cl. D34—15 B

FIG.1

FIG. 2

FIG. 3

FIG. 4

FIG. 5

FIG. 1 is a top plan view of a toy frog showing my present design;

FIG. 2 is a bottom plan view thereof;

FIG. 3 is a side elevational view of such toy, the opposite side being the mirror image of this view;

FIG. 4 is a front elevational view thereof; and

FIG. 5 is a rear elevational view of the toy frog showing my present design.

I claim:

The ornamental design for a toy frog, substantially as shown and described.
